UNITED STATES PATENT OFFICE.

JACOB J. SCHALLER, OF CHICAGO, ILLINOIS.

REVOLVING DOOR.

1,295,607.

Specification of Letters Patent. Patented Feb. 25, 1919.

Application filed August 23, 1917. Serial No. 187,750.

To all whom it may concern:

Be it known that I, JACOB J. SCHALLER, a citizen of the United States, residing at Chicago, in the county of Cook and State of Illinois, have invented a new and useful Improvement in Revolving Doors, of which the following is a specification.

My invention relates to an improvement in the class of revolving doors in which wings radiate from a rotatory axis within a passageway-forming casing and are foldingly collapsible for the primary purpose of rendering the door panic-proof.

In the accompanying drawings, Figure 1 is a plan sectional view of a revolving door involving my invention in a preferred form of its embodiment; Fig. 2 is a broken view in plan section showing the wings in their folded position; Fig. 3 is a vertical section taken through one of the hinges connecting a wing with the center-post, on line 3—3, Fig. 4; Fig. 4 is a section on line 4—4, Fig. 3, and Fig. 5 is a view showing the two hinge-members in unassembled relation with the connecting links and spring and stop-devices on the members.

The casing 6 shown comprises the usual members of arc-shape in cross-section forming the passageway, with an axially rotatable central post 7, from each corner of which radiates a wing, four wings being represented in Fig. 1, numbered, respectively, 8, 9, 10 and 11, hinged to the post and separably connected as by chains 12 for causing the door to be operated in the ordinary manner, under normal conditions, by passing through the passageway.

The primary object of my invention is to provide a hinged construction of the post and wings whereby each wing may be turned on its hinge through 270 degrees of a circle, or approximately that extent, to fold the wings into the parallel relation represented in Fig. 2, when desired, as in case of panic, or to have the door in collapsed condition for any other purpose. That object is accomplished by the following described construction.

The post 7 is of square cross-section with rounded corners. Each wing is a solid structure, being rigid or non-sectional throughout; and it is hinged at its inner edge to the post, that edge being rounded like the adjacent post-corner, and has flexible weather-stripping 13 let into it. The hinge-connections are provided at proper intervals

along the rotary post, thus near its upper and lower ends, and also at one or more intermediate points, as may be required. Each hinge comprises two link-connected members. The members 14, of metal, are let into the post corners and may be fastened in place by screws, represented at 15 in Fig. 5. This member is centrally bored longitudinally to accommodate a pintle 16 and is formed at intervals on its face, which is rounded to conform to the post-corner, with sockets 17, of which two are represented, and at corresponding intervals at its back with tubular housings 18, projecting rearwardly into the post, for spring-pressed studs 19. The other hinge-member 20, also of metal, is let into the rounded wing-edge and may be fastened by screws, as represented at 21. This member has sockets 17^a formed in its rounded face to register with those in the companion-member, and is, like the member 14, bored to receive a pintle 16^a; and the member 20 is provided with housings 18^a extending backwardly from the inner ends of the sockets 17^a and containing, like the housings 18, spring-pressed studs 19^a. Similar links 22 fit at corresponding ends in the sockets of each hinge-member 14 and are rotatably held therein by a pintle 16, and they fit at their opposite ends in the sockets 17^a of the companion hinge-member 20 respectively registering with the sockets 17. The opposite ends of each link, which should be rounded, as shown, contain depressions 23, each in position to register with an adjacent spring-pressed stud when the corresponding door-wing is in its normal position, represented in Fig. 1, of radiating from a post-corner, to admit the stud into the depression for holding the wing yieldingly in that position.

Chains 12 are represented in Fig. 1 as the means extending between the wings for connecting them; and each chain is shown to be permanently fastened at one end to a face of one wing and to releasably hook at its opposite end into an eye 24 on the opposing face of the next adjacent wing. While the chain-medium is preferred, as being readily and quickly releasable, and also flexible whereby by releasing only one chain the wings may be turned independently on their hinges, any other desired connecting medium may be substituted for the chains.

The advantages of my improved revolving door will be best understood by explana-

tion of its use in a door-way of a building, in the event of a fire or other happening therein rendering it important to avoid obstruction to egress and to prevent panic of the inmates.

- 5 Supposing the wings to extend as represented in Fig. 1 and the egress from the building to be in the direction indicated by the arrow at 25 in that figure. With the 10 chain 12 that extends between the wings 8 and 9 unhitched, persons seeking egress will crowd against them, thereby overcoming the yielding comparatively slight resistance of the spring-pressed studs or stops, and the 15 pressure will turn those wings outwardly on their hinges to the position in which they are represented on Fig. 2, thus through 270 degrees, or thereabout; and in attaining that position they will, respectively, encounter 20 the wings 10 and 11 and turn the latter to extend as represented in that figure, thus causing all of the wings to be parallel between the sides of the casing-passageway, which thus become unobstructed.
- 25 The hinge construction, moreover, enables the rounded inner edges of the wings to meet the rounded post-corners, whereby not only the desired full extent of turning the wings is attainable, but there is no appreciable 30 space between the meeting surfaces, so that the door, in its normal operating condition, is practically draft-proof, though the strip 13 may nevertheless be provided to effectively seal the joint.
- 35 I realize that considerable variation is possible in the details of construction thus specifically shown and described, and I do not intend by illustrating a single specific or preferred embodiment of my invention to 40 be limited thereto; my intention being in the following claims to claim protection

upon all there may be of novelty in my invention as broadly as the state of the art will warrant.

I claim:

1. In a revolving door, the combination of a rotatable center-post, hinge-members countersunk in the post, wings having hinge-members countersunk in their inner edges, said post and wing hinge-members presenting opposing sockets, links pivotally confined at their opposite ends in said opposing sockets to permit the wings to be extended radially from the post and to be turned, for folding them, independently of each other 55 on their hinges through approximately 270 degrees of a circle, and spring-stops on the hinge-members for engaging the link-ends to yieldingly hold the wings in their radiating position.

2. In a revolving door, the combination of a rotatable center-post of square cross-section having rounded corners, hinge-members in each corner of the post, non-flexible one-piece wings having rounded inner edges, 60 hinge-members in said edges of the wings, said post and wing hinge-members presenting opposing sockets, links pivotally confined at their opposite ends in said opposing sockets to hold the inner wing-edges in 70 close relation to the respective post-corners and permit the wings to be extended radially from the post-corners and to be turned, from any angle against opposite post-sides independently of each other on their hinges 75 through approximately 270 degrees of a circle and be folded to extend side by side parallel with each other, and means for releasably connecting the wings one with another in their radiating position.

JACOB J. SCHALLER.
